OTHER PUBLICATIONS

U.S. Appl. No. 29/683,548 of Huliyar et al., titled "Motor Grader," filed Mar. 14, 2019 (unpublished).

Primary Examiner — Mark A Goodwin

(74) *Attorney, Agent, or Firm* — Saidman Design Law Group

(57) **CLAIM**

The ornamental design for a motor grader, as shown and described.

DESCRIPTION

FIG. 1 is a perspective view of a motor grader showing our new design;

FIG. 2 is a left side view thereof;

FIG. 3 is a right side view thereof;

FIG. 4 is a rear view thereof;

FIG. 5 is a front view thereof; and,

FIG. 6 is a top view thereof.

The broken lines illustrate structure or features which form no part of the claimed design.

The drawings include surface shading which represents contour and not surface ornamentation.

1 Claim, 5 Drawing Sheets
